COIN OPERATED MACHINE

John C. Wahl, Chicago, Ill., assignor to Lion Manufacturing Corporation, Chicago, Ill., a corporation of Illinois

Application August 2, 1938, Serial No. 222,615

7 Claims. (Cl. 194—48)

This invention relates to a coin operated machine.

More particularly it relates to a dual type of machine, wherein are embodied at least two coin controlled mechanisms, which mechanisms may be conjointly operated or individually operated, said mechanisms to be respectively coin released, and a common manual means serving to operate either or both as desired.

Such machine may in practice take the form of a vender or dispenser in which two separate dispensing mechanisms are provided, which individually are coin controlled respectively by coin handling mechanisms, and a common manual operating means being present and set by the coin handling mechanisms so that the manual means when moved will operate the dispensers. Of course, only the dispenser selected for coin operation should work and therefore that dispenser which is not coin released should not work, or if both dispensers are simultaneously coin released and selected, then both should work upon operation of the common manual means.

A duplex machine of this type has many desirable advantages; for instance, it is compact and while occupying only the space of a single machine produces all of the results of two machines.

The main object of the invention is to provide a novel coin operated machine.

Another object is to provide a dual form of machine having separate coin released, manually operated means, controlled by a common operating member.

Still another object of the invention is to provide a compact machine of the type stated, which will be efficient and fool-proof in operation.

Another object is to provide a machine, housing at least two dispensers, individually released, or locked by respective coin handling mechanisms depending upon whether the latter mechanisms receive a coin, there being a manually moved means operable to work one or both of the dispensers if they have been coin released and set for operation.

Other important objects will become apparent to those versed in this art as the disclosure is more fully made.

Briefly, such objects may be achieved by the illustrative example of the invention herein chosen for the sake of disclosure, in which form a housing or support is provided carrying two, spaced, separate slide type article dispensers. The support carries two coin handling and re-

lease mechanisms provided respectively for the dispensers, each coin handling mechanism having means for allowing a coin to come to rest in a so-called operating position. In the latter position the coin serves to release a rock shaft for operation by a manually swung lever. This rock shaft causes operation of means positively to move the coin in the handling mechanism from its operating position to a display position, where the coins used are displayed temporarily; thus discouraging persons from using fraudulent coins. When the rock shaft swings it also operates means to move the slide dispensers; however, if no coin is held momentarily in a coin handling mechanism at the operating position, then means is set to lock the corresponding dispenser, whereby it cannot operate, even if the said rock shaft is operated by the hand lever in working the other dispenser. So much will suffice in giving a general understanding of the structure of the improved coin operated machine, which is shown in detail in the accompanying sheets of drawings, wherein:

Figure 1 is a general front elevational view of the machine;

Figure 2 is an enlarged, front elevational detail view of a part of the coin controlled mechanism;

Figure 3 is a general side elevational view of the machine;

Figure 4 is a view similar to Figure 3 but showing the parts in a slightly different position;

Figure 5 is a rear elevational view of the machine with the back wall of the cabinet removed to expose the interior mechanism;

Figure 6 is a side elevational view of the interior mechanism with the cabinet or housing removed; and,

Figure 7 is an enlarged, front elevational, view of one of the coin handling mechanisms.

The improved coin machine may be in the form of a dispenser and comprises a suitable cabinet 15 having a front wall 16, opposite upper portions of which are formed with elongated vertical, glass covered, display openings, or windows 17.

Above, and to one side of the windows is a circular opening in the wall 16 through which is projected the coin entrance sleeve 18 carried at the upper end of front plates 19 disposed in an upright manner and tilted rearwardly as shown out of a vertical plane.

It will be understood that these plates 19 constitute the support or frame for the respective coin handling and release mechanisms of which two are provided in this machine, since two dis-

pensers are to be controlled. Each coin handling mechanism is a duplicate, in all respects, of the other; however, for the sake of compactness, one is right hand and the other is left hand. Thus, it will be understood hereafter, when only one coin handling mechanism is being described, that the other is the same.

Inside the cabinet 15 is suitably positioned a frame comprising opposite, spaced side members 20, the front edges of which have secured thereto a rear plate 21 somewhat thicker than the front plate 19. These two plates 19 and 21 are substantially coextensive in size and shape and lie flatly one on the other, both being inclined from the vertical, as shown, and serving together as the mounting means or support for the coin chute or handling mechanisms. These two plates as a unit are secured to the front edges of the two spaced side frame members 20 by bolts 22 which enter respective holes 23 provided in the plates 19 and 21 for that purpose.

At the lower portion of the cabinet 15 the frame 20 carries a cross rock shaft 24, one end thereof extending outwardly through an end wall of the frame where it carries fast thereon an upright operating member in the form of a hand lever 25. This shaft 24 when freed by the coin handling mechanism to be described, can be rocked by the lever 25 to operate, or cause to be operated, any suitable means, such as the dispensers to be described. One end of the shaft 24 inside the cabinet and adjacent one side member 20 carries fast thereon a lever 26 and an oppositely extending boss 27 also fast thereon. Thus the parts 26 and 27 rock with the shaft 24. This end of the shaft 24 also carries loosely thereon a quadrant shaped member 28, one corner of which carries a transverse pin 29 engaging behind an edge of the arm 26, as shown. The quadrant 28 at another point carries a rigid, oppositely extending transverse pin 30 which normally is held in the narrowed end of an opening 31 formed in the proximate frame member 20, because of the pull of a spring 32 connected between the quadrant 28 and member 20 as shown in Figure 6. The quadrant between its pins is formed with a hump 33 normally engaged by a lock lever 34 pivoted intermediate its ends at 35 to the frame 20 and pulled by a spring 36 to engage one end of the lever 34 with said hump 33 as shown in Figure 3. A notch in the quadrant is formed at 33' adjacent the hump. A lifting link 37 has one end pivotally connected to the operative end of the lever 34, as shown. Only one of the coin handling mechanisms includes a link 37 and there is only one quadrant 28.

Adjacent the boss 27 the frame 20 by means of a pin 38 pivotally carries a lever 39 one end of which is engaged with the boss 27 while the other end has pivoted thereto, one end of an upright link 40.

The link 37 is controlled by a proper coin held in an operating position, as will later appear, to cause the link 37 to be held raised whereby the latch 34, 33 is released to enable operation of the lever 25 and shaft 24. At the same time the link 40 through boss 27 or lever 39 may be pulled down to operate mechanism to be described for positively moving a coin downwardly from its operating position into a coin display escalator, said escalator also being driven as the result of the upward movement of said link 40.

The link 40 has its upper end pivotally connected to a bell crank 41 (see Figure 6) pivoted on a cross shaft 42 carried on members 20. The

other corner of the member 41 carries a rigid transverse pin 43 located in the notch 44 of the downturned end of a spring pulled lever 45 which is rotatably mounted between its ends on a cross shaft 46 carried in the frame 20. This lever 45 (there being one on each side) extends upwardly and forwardly and has a head end 47 shaped to extend forwardly through a vertical, narrow, elongated slot 48 (see Figures 6 and 7) formed through the superimposed plates 19 and 21.

5 A latching lever 49 is also pivoted on the fulcrum 46 for each lever 45, the same having a hooked free end to form a notch 50 for a purpose later to be made known. Each lever 49 has a transverse extension 51 arranged over the back edge of the associated large lever 45 and a spring 52 connected between the extension 51 and lever 45 as shown in Figure 6 causes the levers 49 to move with levers 45 although the two are independently pivotally mounted on the fulcrum 46. Each lever 45 is positively moved down as will appear and the spring 52 pulls latch lever 49 down with it, although the levers 45 make a much longer down stroke since it is necessary for their heads 47 to travel substantially the length of the respective slots 48.

10 The upper end of the link 37 as shown in Figure 6 is pivotally connected to a proximate transverse pin 53 fastened to a forwardly extending arm 54 integral with a sleeve 55 made fast to a cross shaft 56 journaled in the end plates 20. (See Figure 2.) The arm 54 at each end of shaft 56 is made wide so that it can rigidly carry two vertically spaced, transversely extending, parallel pins 57 and 58. Each pin 57 extends into an opening 59 larger in diameter than the pin, and formed in an arm extension 60 extending forwardly from respective upright levers 61 loosely pivoted intermediate their ends on the shaft 56. A spring 62 is connected between an upper part of each lever 61 and the other pin 58 on arm 54. Relative movement, because of the loose connection 57, 60 can take place between link 37 and the loose levers 61. 15 While there are two levers 61, it will be understood that they are disposed one on the rock shaft 56 at each end of the latter, but that only one arm 54 has a depending link 37, because there is only one sector 28 associated with rock shaft 24. These levers 61 have each a lower extension 62' and a rear extension 63, which extensions in this disclosure may be considered to serve as counterbalancing means for the lever 61. The upper ends of the levers 61 are turned upwardly 20 and forwardly and at their upper terminal ends carry a transverse pin 64 for a purpose to appear.

25 There has now been described all of the auxiliary operating mechanism cooperating with the coin handling mechanisms and released thereby for operation. The specific details of the coin handling mechanisms, both of which are alike, will now be described.

30 The plate support 19 and 21 of each mechanism, has an upper offset portion (see Figures 1 and 6) and a lower offset portion, the upper portion serving to carry the coin entrance passage and testing means, while the lower offset portion forms the display means cooperating with a coin escalator.

35 Taking the upper offset portion first, it will be seen that the plates 19 and 21 between them are provided with a downwardly extending coin drop passage 65 leading from the coin drop opening 18. This passage at its lower end curves to 40 the right as seen in Figure 1 and terminates in

a position where the lower end of the slot 48 would approximately diametrically aline across the face of a coin lodged at the lower end of said passage 65. In this latter position the coin, one of which is shown in dotted lines at 66 in Figure 7, is considered to be in the operating position where the coin machine parts may now be operated by the lever 25. (See also Figure 6.)

The two plates 19 and 21 are held flatwise together by screws 67. The front plate 19 is formed with a vertical slot 68 having a lower extension 69 extending across the offset portion of the coin passage 65. The upper part of slot 68 has a narrow upwardly extending extension 10. The rear plate 21 in back of the slot 68, 69 is formed with a similarly shaped slot 71 of considerably greater width, in fact of a width designed to conform to the diameter of undersized coins, such as pennies. The penny will be assumed herein to be undersize and the proper size coin will be considered the five cent piece. Thus, the back side of the coin drop passage 65 in advance of the operating position designated by coin 66 will be open and since the plates 19, 21 lean back, it follows undersized coins such as dimes and pennies will fall from the passage 65 through slot 71 before they can reach an operating position. Such rejected coins can be received by any suitable chute, not shown, and directed to any out of the way place in the cabinet, as may be desired.

On the front face of plate 19 on opposite sides of the slot 68 are ears 72 for mounting a cross shaft 73 on which is rockable intermediate its ends, a peculiarly shaped lever 74 having an upper hooked portion 75 passed back through the upper left hand part of slot 68. This upper portion may be weighted as at 76 and 77 to provide proper balance against the lower end of the lever which is formed as an extension 78 movable in slot extension 69 and normally lightly held by the counterweight described in a position to be engaged by a coin or the like moving down the passage 65. This extension 78 cooperates with slot 71 to deflect undersize coins from the passage 65 in an obvious manner and as fully disclosed in applicant's co-pending application Serial No. 222,247 filed on July 30, 1938. Adjacent the upper end of the slot 68 above shaft 73 one edge of the slot is provided with a piece 79 to project into the slot and against the top edge of which the rear end of the tail member 75 abuts to limit the movement of the latter in an inward direction. The weights 76 and 77 being forward of the pivot 73 act normally to swing the tail 75 outwardly and hold the extension 78 inwardly so that a coin moving down the passage 65 must engage same.

The plates 19 and 21 below the coin drop spout 18 and to one side thereof have a transverse slot 80 formed therethrough as appears in Figures 6 and 7, the front portion of the slot tapering downwardly as at 81. The back sides of the plates 21, as seen in Figure 5, are provided with pairs of spaced ears 82 carrying a transverse shaft 83. Pivotaly hung from this shaft is a lever 84 shaped as the tail of an enlarged head portion 85 provided with means 86 to add counterweights to hold said levers normally back with their tails 84 extending forwardly into the slots 68. Secured to the head 85 of each lever is a laterally extending stop member 87, having a horizontal portion formed with a notch 88 and a front extension 89 curved downwardly to co-

operate with and fit into the slot 80 already described. One edge of this head 87 proximate the entrance to the coin drop passage 65 will engage the edge of one coin when two coins are 5 simultaneously fed into the respective spouts 18 to make it possible for one coin only to enter a passage 65 and move therealong as will later more fully appear. A coin in the operating position, such as the coin 66 serves a cooperating locking function in this connection, as will next appear.

Looking at the back side of each plate 21, as shown in Figure 5, it will be seen that on opposite sides of the upper end of the vertical slot 48 there are provided two spaced ears 90, carrying a cross shaft 91 on which is hinged, intermediate its ends, a generally upright lever 92. Said levers each have a right angularly turned, upwardly extending portion 93 disposed in the notch 88 of a proximate member 81. These levers extend quite a distance below their fulcrums and at their lower ends are formed with forwardly extending portions 94 and rearwardly extending fork portions 95. The forward portion 94 extends through a vertical slot 96 formed in the plates 19 and 21 adjacent slots 48 so that the portion 94, as shown in Figure 6, may press against a coin held in the operating position in the passage 65, such as the coin 66 shown. 20 The balanced weight of said levers 92 is such that the part 94 will tend to pass into the slots 96, unless a coin is in the operating position and then, of course, the part 94 will abut the back side of such coin. As shown in Figure 6, when a coin as 66 is abutted by the part 94, the lever 92 is locked against movement so that the upper part 93 thereof is pressed forwardly in the notch 88 to hold the stop member 89 forwardly in the slot 80 to prevent ingress of coins into the entrance to the passage 65.

The plate 21 along one edge is formed with a hook 96'. (See Figure 7.) Pivotaly carried on a pin 97 in a space 98 provided between the plates 19 and 21 is a latch member 99 which has a hook end 100. A spring 101 connects between the hook 100 and hook 96' normally to pull the latch 99 so that the same may project its end into the slot 96 and abut the lower edge of a coin, such as coin 66, and positively hold same in the operating position at the lower end of the passage 65 as shown. The movement of said latch 99 is limited by one edge of the space 98.

As shown in each coin handling mechanism, one edge of the plates 19 and 21 is complementarily extended laterally to provide ears 102 between which is secured, by a screw 103, a horseshoe magnet 104, positioned horizontally, with the end of the lower leg rounded or curved as at 105. This magnet has its field disposed proximate a side edge of the coin drop passage 65 in a manner best to attract magnetic slugs dropping down the passage 65. (See Figure 7.) The ears 102 carry a small receptacle 106 therebelow and a slot 107 is formed in the rear plate 21 laterally from the passage 65 and directed toward the open top of the box 106 so that a magnetic slug will be magnetically attracted and drawn side or edgewise to the left, as viewed in Figure 7, and with the aid of gravity, cause it to roll under and around the arcuate magnet leg 105 to pass through the slot 107 and into the box 106.

Going back now to lever 92, the lower end thereof is forked as at 95, said fork spanning the pin 64 on the upper end of the lever 61. Play

is permitted between the fork 95 and pin 64. The escalator for moving the coins out of the coin handling mechanism will next be generally described.

As shown in Figure 6 the back plate 21 at its lower offset portion below the operating position of the coin 66 carries by means of screws in spaced relation to the plate 21, an auxiliary plate 108 of irregular shape. Below the operating position of the coin 66, the rear plate 21 is cut out to form a long vertical coin display passage 109 having an abutment edge 110. The top plate 19 has its lower offset portion extended slightly to overhang the abutment edge 110 whereby coins moving down said display passage 109 are properly guided and cannot jump or be forced out. It will be understood that this display passage 109 is directly under or behind the window 17 in the cabinet or housing 16, so that the coins in the passage 109 are readily visible at all times.

Upper and lower portions of the plate 108 carry an upper shaft 111 and a lower parallel shaft 112. A front stationary plate 113 is carried on the shafts 111 and 112. Each shaft carries loosely, a reel mechanism for an endless escalator band. Each reel is numbered 114. Each reel for each coin handling mechanism is formed at angular intervals on its periphery with driver prongs 116 and a spool surface for an endless steel band 117, which has spaced slots 118 to receive the lugs 116 whereby to drive the band. The band approximately on its center line is formed with large coin receiving slots 119 (see Figure 7), which individually may receive coins in the manner indicated. The width of the slots 119, as well as their length may be varied in different bands in accordance with the size of the coins to be handled. Said reels at angular intervals are formed with pockets, as shown in the co-pending application mentioned, to receive coins sticking through the band 117 and slots 119.

The plates 113 each have an outstanding ear 123 carrying a pin or roller 124 serving to keep the bands 117 properly guided and tensioned.

Carried fast on the upper shaft 111 of each coin handling mechanism adjacent to but on the back side of the upper reel 114 is a toothed driver disk 133 positioned on the front side of the plate 108 (see Figure 5), said plate having a large arcuate slot 134 formed therein, as shown. The shaft 111 on the back side of the plate 108 has fast thereon a lever 135 pivoted intermediate its ends. This lever carries a pin 136 to which is connected a spring 137 in turn connected to a pin 138 mounted on the plate 108. This spring 137 normally acts to pull the right hand end of the lever 135 down as viewed from the rear. The upper right hand corner of this lever 135 carries a pivot pin 139 to which is pivoted a driver pawl 140 engageable with the teeth on disk 133, said pawl 140 having a hump 141 for a purpose to appear. A pin 142 on the pawl 140 has a pull spring 143 connected to it, the spring having its other end connected to the lever 135. The spring 143 holds the pawl 140 in duty against the toothed disk 133. An upstanding part of the plate 108 carries a pin 145 against which the hump 141 engages to limit the stroke of the pawl 140 and lever 135.

The back side of the lever 135 at its upper left hand corner as viewed from the rear in Figure 6 carries a rearwardly extending pin 146. Pivotedly connected to the pin 146 at its lower end

is an upstanding link 147 the upper end of which is pivotally connected by means of a pin 148 to the lever 45.

The lever 92 heretofore described, at its lower end carries a laterally extending pin 154 positioned in the path of movement of the lever 49 so that its hook portion or notch 50 may at times engage over and latch with the said pin 154.

The coin escalator mechanisms and coin testing mechanisms for each unit above generally described form no part of the present invention, since they are more adequately disclosed and covered in a co-pending application of this application filed on July 30, 1938, Serial Number 222,247, for Coin handling mechanism.

The floor of the coin machine at each end carries a dispenser of any type, the ones herein shown being of the slide type. Each dispenser comprises a slide 155, as shown in Figures 5 and 6, carried appropriately for sliding movement, to and fro, on the floor of the machine. These dispensers are well known in the art and include respective upright magazines 156, containing stacks or columns of superimposed flat articles of any character to be dispensed. Such articles are shown at 157. The slides 155 have respectively a cut out opening 158 therein conforming to the size and shape of the articles to be dispensed. In the normal position each slide is positioned with its opening 158 directly under a magazine 156 so that by gravity an article 157 rests in said opening 158. Such article rests on the floor numbered 159, which has an article discharge vender opening 160 formed therein offset from each magazine 156, as shown. As appears in Figure 6, when the slide 155 is moved to the right the article 157 trapped in slide opening 158 is moved with said slide until it is positioned over the opening 160 to drop therethrough, and thereupon such article is received by means of chutes not shown in respective troughs 161, shown in Figure 1, where the operator can take the article.

The shaft 24 at each end has loosely carried thereon a pendant lever 162 having a pin 163 at its lower end to fit into a saddle member 164 carried rigidly on the top side of each slide 155. A leg of a coil spring 165 surrounding the shaft 24 is attached to the levers 162 respectively, while the opposite end of each said spring is fastened to the shaft 24. These springs 165 are quite stiff so that normally they will not give and thus act to move the arms 162 as though they were rigidly connected to the shaft. However, if the slides 155 are held locked then the springs 165 would yield and not move the lever arms 162 so that the dispenser slide 155 associated with it could not operate.

It so happens that if the coin handling mechanism associated with a dispenser is not properly coin released, that means is automatically made effective to lock the associated slide 155 and prevent its operation. Such means comprises a bell crank lever 166, there being one on each side, journaled on a respective pin 167 carried in a proximate wall member 20. This structure appears in Figures 5 and 6, where one leg of each lever 166 has pivotally connected to it a depending lock rod 168, the lower ends of which respectively are guided in a vertical sleeve 169 carried on the slides 155. Each slide 155 has a bore registering with said sleeve and adjacent each slide 155 the floor 159 is provided with a hole 170, so that the rod 168 may at times, when desired, drop by gravity normally through a sleeve 169, slide 155, and into a hole 170 to lock the said slide 155

releasably to the floor 159 against movement in an obvious manner.

The opposite leg of each bell crank lever 166 carries a transverse pin 171 which pins are positioned to be abutted by the respective parts 95 of the levers 92. Thus with a coin in the operating position as appears at 66 in Figure 6, the part 95 of lever 92 is held back in such a manner that bell crank lever 166 is rocked to pull up on the rod 168 to free it from the hole 170 whereby to unlock the slide 155 from the floor 159 to permit the slide to make a dispenser operation. These rods 168 flex when the slides 155 are moved and the normal resistance of the rods 168 is not sufficient to make the springs 165 effective to swing the arms 162. Said springs 165 yield only when the rods 168 are locked to the floor 159 in a hole 170. These dispensers and their lock means are illustrative forms of what may be used in practice.

This completes the description of the details of the improved coin operated machine. The operation thereof will now be summarized.

The purpose of the structure, of course, is to pass proper coins through the handling mechanisms to cause release of the one sector member 28 so that the one hand lever 25 may be swung to operate the dispensers of the coin controlled machine; at the same time causing linkage to be effective for moving coins from the coin passage 65 into the escalator display means, and lastly, to cause operation of one or the other, or both dispensers 155.

When a single authentic coin, let us say a five cent piece, is placed flatwise into the spout 18 of one coin handling mechanism, it will enter the upper end of the coin passage 65, pass the head 87 which is held back by the balanced lever 84; also passing the portion 75 which is held forwardly by the weighted lever 74 and its tail 78 as it slides down the passage 65 and finally comes to rest in the operating position as indicated at 66 in Figure 7. Here the stop dog 99 serves to hold the coin. In this position the coin 66 swings back the tail portion 94 of the balanced lever 92 so that the upper end 93 of the latter moves forwardly in the notch 88 of the head 87, whereby to swing the latter forwardly. This results in placing the stop 89 which is extended into and through the slot 80 in a forward position, so that no coin for the time being can drop below the upper end of the passage 65 where it will be held by said projection 89.

With the lower end of the lever 92 thus pushed back by the coin 66, as seen in Figure 6, the edge of the fork 95 on the lower end of said lever 92 engages and pushes the shaft 56 slightly clockwise as viewed in Figure 6. Thus, even though only one coin handling mechanism receives a coin in the operating position, nevertheless since the rock shaft 56 rocked, the other lever 61 on the opposite side is also correspondingly moved. Thus, the front end of the arm 54 is raised so that its pin 53 will pull on and raise the link 37 an amount sufficiently to lift the right hand end of lever 34 as shown in Figure 6. The operator may now grasp the lever 25 and swing same forwardly to rock the coin machine shaft 24, since the latter is freed. When the shaft 56 is rocked, both arms 54 raise at their front ends by the structure shown in Figure 2, even though only one coin handling mechanism is operated.

This brings about a situation where it would appear every time the rock shaft 56 is rocked by a coin in only one coin handling mechanism at

the operating position thereof, that the dispenser on the opposite side would also work when the shaft 24 is rocked. But this is not so, for in the other coin handling mechanism that did not receive a coin we find that the lever 92 is swung with its portion 94 projected forwardly through the associated slot 96 since no coin is in the associated operating position to hold the part 94 back. Consequently, the associated fork part 95 is also in its forward position to free the bell crank 166 as its pin 171 cannot be pressed back by the part 95. It follows, then, that with lever 166 free, the associated rod 168 by gravity will drop through the slide 155 below it and into hole 170 to lock the said slide 155 to the floor 159 against operation. This is the normal position of these parts when no coin is in the operating position, as will now be readily understood.

As the shaft 24 rocks counterclockwise as viewed in Figure 4 the arm 26 engages pin 29 and rocks the quadrant 28 to the left or forwardly against the pull of the spring 32. With the parts so released by a proper coin the stop end of lever 34 will clear and ride over the hump on the sector 28 just to the rear or right hand of the notch 33'. As the shaft 24 so rocks, the abutment 27 rocks in the same direction, whereby to push up on the front end of the lever 39, causing the link 40 to be pulled downwardly. As said link comes down the bell crank lever 41, as best seen in Figure 6, is swung to cause its pin 43 to move rearwardly in notch 44 of lever 45 to swing the forward end 47 thereof downwardly in the slot 48. At the same time the lever 49 also swings down by the pull of the spring 52, until the hook notch 50 thereof rides over the pin 154 to lock the lever 92 and with it, of course, the tail 94 which is engaging the coin 66 in its operating position. With the lever 92 temporarily latched it cannot at this instant swing, so the upper stop arrangement 93, 89 is still effective to prevent passage of coins down the passage 65. As the lever 45 continues its down stroke, its front nose end 47 engages the coin in the operating position and presses it downwardly with a force sufficient to retract the yieldable stop dog 99.

The coin 66 now passes below the dog which springs back into stop position to stop the next coin entering the operating position. The first mentioned coin now enters the upper end of the display passage 109 where it engages in a slot 119 in the endless steel band 117.

As the lever 45 swung down it pushed down on the link 147, shown in Figure 5, to operate the lever 135 and pawl 140. Thus the ratchet disk 133 was turned one step and the two reels 114 are simultaneously turned one step in the same direction. This moves the run of the band 117 adjacent the abutment 110 downwardly, and with the coin carried therein, it follows the latter is moved one step down in display position behind the window 17 and held there until the band 117 is again moved. As shown in Figure 1, five coins are simultaneously held in display position by the escalator band, the coins being fed in at the top as described, and eventually dropping out one at a time from the low end of the passage 109 into a cash box or any other desired place.

When the lever 25 is now released the spring 32 pulls the quadrant rearwardly until pin 30 engaging in the rear end of the opening 31 stops same, this position being shown in Figure 3. The parts now operate in the reverse order and assume their initial operating positions. That is the link 37 moves down; the link 40 moves up, the

lever 45 is moved up, and likewise, the latch 49, thus freeing the lever 92 so that under its balanced weight the tail 94 is swung forwardly and the top part 93 thereof is swung rearwardly to free the stop member 89. The mechanism is obviously now ready for another coin to drop through passage 65 to the operating position as heretofore described.

It is quite plain now that where one coin handling mechanism has been set by a coin in operating position as at 66 that the lever 92 has been moved, thus also moving proximate lever 166 to raise the associated rod 168 and then when rock shaft 24 moves, the arm 162 can move the dispenser 155 on the same side. The opposite dispenser is locked and cannot work as has been explained. If a coin is in both handling mechanisms at the same time, at the operating positions 66 thereof, then the one lever 25 by movement of shaft 24 causes both dispensers to be freed and to operate simultaneously in an obvious manner.

If a magnetic slug is used it will be attracted and moved sidewise by the magnet 104, the slug with the aid of gravity rolling around the rounded leg 105 of the magnet and through the side slot 107 into the receptacle 106, as shown in Figure 7, so that such fraudulent coin cannot reach the operating position.

When no coin at all is used, the lever 92 by its weight is so balanced that the tail 94 extends forwardly through the slot 96. By means of pin 64 the lever arm 54 is rocked forwardly causing the link 31 to be held down. It follows, as shown in Figure 4, that before hand lever 25 can be rocked forwardly very far, the tail on the end of the lever 34 will catch in the notch 33' and lock the sector 28 as well as the lever 25 against a full stroke. It follows, therefore, that the coin machine cannot be released and a dispenser cannot operate, if no coin is in the operating position holding the tail 94 of the lever 92 back in a corresponding coin handling mechanism.

Undersized coins, because the passages 65 lean back from the vertical, hit the respective tail extensions 78 and are deflected thereby flatwise rearwardly out through the enlarged slots 71 as has been explained.

When a coin is in the operating position, as at 66, in either coin handling mechanism, another coin cannot be passed down the passage 65, because the first coin 66 holds the tail 94 of lever 92 back and the portion 93 thereof forwardly to press the stop head 89 into a position to obstruct the upper end of the passage 65 and prevent the second coin from passing down the passage 65 against the previous coin held in the operating position. This safe-guard prevents the possibility of successive coins jamming in the passage 65.

If unauthentic coins or slugs should pass the above safe-guards provided, and enter the operating position to enable release of the coin machine, it is but an instant before such coin will be lodged in the display position passage 109, where for five operations the improper coin will be displayed to shame the player.

It can now be seen that an improved mechanism has been provided for the purposes stated, which achieves the objects heretofore recited. Obviously, more than two coin handling and releasing mechanisms and dispensers may be used if desired within the bounds of this invention.

The intention is to cover all changes and modifications of the example herein chosen for illus-

trative purposes, which do not in fact constitute departures from the spirit and scope of the invention as expressed in the appended claims.

What is claimed is:

5. In a coin operated machine, a coin handling mechanism including a pivoted member adapted to be moved into an operating position by a coin held in the mechanism, a cross rock shaft operatively associated with said mechanism, said mechanism including means carried on the rock shaft and operable by the associated pivoted member to rock the shaft, a second rock shaft, means to lock the second shaft releasably, manual means to rock the second shaft when it is freed, and means controlled by a coin in the operating position in said mechanism and movable by said means on the first rock shaft to free the second rock shaft for operation.
10. 2. In a coin machine, a first rock shaft, a second rock shaft, means to lock the second rock shaft, independently operable coin handling devices associated respectively with the first rock shaft each including coin moved means to rock the first rock shaft, additional means associated with said devices to free the second rock shaft, manual means to rock the second shaft when same has been freed, normally inoperative dispensers included in the machine respectively for each coin handling device, means causing said dispensers to operate when the second rock shaft has been rocked, and means to hold that dispenser inoperative when its associated coin handling device does not receive a coin.
15. 3. In a coin operated machine, a plurality of dispensers, common means for jointly or severally causing operation of the dispensers, means for normally latching the common means against operation, a plurality of coin handling mechanisms respectively corresponding with the dispensers and associated therewith, means for normally latching the dispensers, and means controlled by the presence of a coin in a handling mechanism to cause unlatching of the common means and corresponding dispenser for operation.
20. 4. In a coin operated machine, a plurality of individual dispensers, separate coin receiving mechanisms provided respectively for the dispensers, rockable means common to said dispensers to operate same, means for releasably locking said operating means when no coin is passed through any coin receiving mechanism, means operable by any coin receiving mechanism including parts therein to receive and hold a coin for moving the locking means and freeing the common means when a coin is passed into said coin receiving mechanism, and a single manually operable member for operating the released common means to effect operation of the dispenser corresponding to the coin receiving mechanism which received a coin.
25. 5. In a coin released machine, a support, a rock shaft journaled therein, a pair of movable dispensers positioned proximately to the rock shaft, means individually and releasably locking the dispensers against movement to dispensing positions, a manually operable lever on the support to rock the rock shaft and connections from the shaft to the lever to cause operation of any dispenser that may be unlocked, means releasably to lock the manually operable lever against operation, and coin freed mechanism respectively provided for each dispenser and including coin moved parts to unlock the lever and a selected dispenser so that when said lever is operated the

coin freed dispenser may be moved to a dispensing position.

6. In a coin released machine, a support, a rockably mounted part carried thereby, a plurality of movable dispensers positioned adjacent the rockable part, means individually and releasably locking the dispensers against operation, manually operable means to move the rockably mounted part and including connections from the part to cause operation of any dispenser that may be unlocked, means releasably locking the manually operable means against operation, and a plurality of coin freed mechanisms respectively provided for each dispenser and each including coin moved parts to unlock the manually operable means and the dispenser corresponding thereto whereby any or all dispensers may be operated upon operation of the manually operable means.

7. In a coin operated machine, a pair of coin handling mechanisms each including a pivoted member adapted to be moved into an operating position by a coin held in a corresponding mechanism, a cross rock shaft carrying in spaced relation thereon rockable members operatively associated respectively with the corresponding pivoted members of said mechanisms, whereby the associated rockable member may act to rock the shaft, a dispenser respectively associated with each handling mechanism, means to operate the dispensers, means normally locking each dispenser, and means governed by a coin in a handling mechanism and operable by a pivoted member to unlock and enable operation of the corresponding dispenser.

JOHN C. WAHL.
